CHARLES SOMMER, OF CHICAGO, ILLINOIS.

Letters Patent No. 89,178, dated April 20, 1869.

IMPROVEMENT IN SAW-MILLS.

The Schedule referred to in these Letters Patent and making part of the same.

To all whom it may concern:

Be it known that I, CHARLES SOMMER, of Chicago, in the county of Cook, and State of Illinois, have invented certain new and useful Improvements in Sawing-Machinery; and I do hereby declare that the following is a full, clear, and exact description thereof, reference being had to the accompanying drawings, making a part of this specification, in which—

Figure 1, plate 1, is an elevation of one side of the improved sawing-machine, showing, by the aid of red lines, a log in position for being sawed.

Figure 2, plate 1, is a vertical section, taken centrally and longitudinally through the log-holding devices.

Figures 3 and 4, plate 2, are vertical cross-sections, intended to show the manner in sawing a log into slabs.

Figure 5, plate 2, is an elevation of one end of the longitudinally and laterally-movable log-supporting carriages.

Similar letters of reference indicate corresponding parts in the several figures.

This invention relates to certain novel improvements on sawing-machinery, which is adapted for sawing up round logs into stuff suitable for being shaped into barrel-staves.

The object of my invention is to utilize stock in the operation of sawing out barrel-stuff from round logs, and to produce the stuff with parallel sides, so that, without further dressing, it is ready for well-known shaping-machinery, to be wrought into staves.

To effect the above object, I make both of the centring and holding-devices of that class of machines which most nearly resembles mine in construction, adjustable laterally, as well as longitudinally and vertically, instead of as heretofore, having said centring-devices either both immovable laterally, or one only of them adjustable laterally.

The adjustments of my machine I also make with respect to a single saw, which is arranged above the centring-devices, and so as to cut in a direction with the length of the grain of the wood, and into the log to a depth less than one-half of its diameter, such saw, by reason of the adjustments of the log, sawing two sets of kerfs, those of one set being radial, and the other tangential to circles described from the centre of the log, as will be hereinafter described.

My method of sawing logs admits of the logs being elevated by the centring-devices, there being no obstruction from a saw placed below these devices; thus great convenience in handling heavy logs is secured.

To enable others skilled in the art to understand my invention, I will describe its construction and operation.

In the accompanying drawings—

A represents a foundation, or bed, consisting of two

horizontal parallel ways, united, in a suitable manner, at their ends, so as to constitute ways for supporting and guiding a carriage, or slide, B.

The carriage, or slide B, is grooved into the upper edges of the ways of foundation A, so that it can be freely moved in a direction with the length thereof, but is prevented from lateral displacement.

This carriage, or slide B, is composed of two parallel ways, suitably united at their ends, and grooved along their upper edges, for receiving, and holding in place laterally, two slides, C C, which carry upon them laterally-adjustable head-blocks, E E, the bases of which are grooved laterally, to receive the tenons, or guides b b, upon the upper sides of said slides.

The slides C are constructed with tenons on their bottom-surfaces, which enter the grooves formed in the upper edges of the carriage B, and thus prevent these slides from lateral displacement, but allow them to be adjusted at different distances apart upon the carriage B, according to the length of the log, or logs to be sawed.

To the bottom side of each slide, a bracket, g, is rigidly secured, through which a screw-bolt, h, is passed vertically, that carries upon its lower end, beneath the bracket g, a transverse bar, n, the ends of which lie beneath ledges, T T, which are upon the inner vertical sides of the guide-ways of carriage B.

The bolt h passes up through the slide C, and through an oblong slot, made through the base D, of the head-block E, and receives upon its upper end a nut, i, by the tightening of which the head-block can be confined rigidly down upon its slide, and this slide confined rigidly in place upon its carriage.

By loosening the said nut i, on each one of the bolts h, the slides C C and the head-blocks will be free, and can be adjusted as may be required.

The slides C C, with their head-blocks, are adjusted nearer to or further from one another, according to the length of the log to be sawed, and the head-blocks may be adjusted laterally, by means of levers, L L, which are pivoted to the slides C C, and connected, by rods a a, to the base-plates of the head-blocks.

Vertical slots, e e, are made through the head-blocks E E, for receiving vertically-adjustable blocks, which carry the centring-dogs G G', between which the logs are centred and confined while being sawed.

The blocks F F' have screw-threads upon them, for receiving nuts, c c, by means of which, and the shoulders d d, these blocks can be rigidly clamped to their respective head-blocks, at proper height for presenting the logs to the saw H.

The blocks F F' are raised or depressed by means of vertical screw-rods P P, which pass loosely through the head-blocks, the slides, and the brackets below the slides, and receive upon them, between, the said brackets and slides, hand-wheel nuts J J.

By turning these hand-wheel nuts J J, the attendant can raise or depress the blocks F F', when the nuts e e are loosened.

The centring-dog holder, or block F', is made tubular, as shown in fig. 2, and receives a longitudinally-adjustable dog, G, which can be thus adjusted by means of a screw, s, and hand-crank, K.

The screw s is tapped centrally into the rear end of the dog G', and so applied to the dog-holder, or block F', that the two dogs can be made to forcibly gripe and hold a log by its ends after the head-blocks and their slides have been rigidly fixed.

By a few backward turns of the said screw s, a log can be loosened, so that it can be turned about its axis.

The saw H is of the circular kind, and is applied upon a shaft I, which has its bearings in the upper forked ends of a standard, N.

The shaft has a belt-wheel, I', upon it, over which a belt passes, that receives motion from any convenient prime mover.

I have now described a machine which is adapted for sawing stuff having parallel sides from round logs, but I do not confine myself to the precise construction of the several parts, as herein described and shown, as these parts may be modified, and their mechanical equivalents adopted in their stead.

For instance, the head-blocks may be moved laterally by means of a lever, having a toothed segment on one end, adapted to engage with rack-teeth formed on or applied to said head-blocks.

The head-blocks may have their base-plates applied to the slides C C, by dovetail tenons and grooves, and the dog-carrying blocks F F' may be raised and depressed by means of racks and pinions.

Again, instead of having the centring-devices adjustable laterally, the necessary lateral adjustment might be made in the saw-shaft and saw, by providing the shaft with movable collars, in such a manner that by loosening these collars, and setting them back, the shaft, with saw, might be slipped in its bearings far enough to have the saw cut the kerfs, which are tangential to circles struck from the centre of the log being sawed.

The collars, of course, are again set up and fastened, after the desired adjustment is effected.

The operation of sawing with the above-described machine is as follows:

The slides and their head-blocks are adjusted and set for receiving logs of a given length, and so that the axes of the dogs G G', will coincide with each other, and stand in the vertical plane of the saw H.

A log, to be sawed, is rolled upon the bed A, upon cross-pieces, temporarily laid thereon, or upon projections of the slides C C, made for the purpose.

The nuts i i, on screw-rods h h, are then loosened, and the dogs brought down, by turning hand-wheel nuts J J, so as to be in line with the axis of the log.

The crank-handle K is then turned, so as to firmly clamp and confine the log in place between the dogs, and the log raised sufficiently high, by turning wheels J J, to allow the saw H to make the proper depth of cut.

In fig. 2, the red lines indicate the log upon the bed A, ready to be gripped by the dogs G G', and in fig. 1, the red lines indicate the log raised, and in the act of being sawed from end to end.

The centring-dogs are sharpened, to enter the log proper distances, by making concavities in them, as shown in the sectional view, fig. 2.

The first cut made through the log by the saw is

in a plane, radiating from the centre, or axis of the log, as shown by red lines in fig. 3.

Before the next cut is made, the log is moved bodily in a lateral direction, or in a direction at right angles to its length, one inch, more or less. The next cut will thus be made in a plane parallel to the first cut, but tangential to circles described from the centre of the log.

The log is then moved backward bodily, and in a lateral direction, two inches, more or less, and another cut is made, in a plane parallel to the first two kerfs.

This leaves two slabs, with parallel sides, adhering, by their edges, to the core, or heart of the log.

I then turn the log one-quarter of a revolution about its axis, and perform the same operation of sawing, and so on, until the log has been sawed, say, twelve times.

This mode of sawing will produce, for the first cuts, eight slabs, of equal width and thickness, and leave four intermediate segments, which are sawed in the same manner as above described, and produce slabs of less width, leaving narrow angular pieces, as indicated in red lines, figs. 3 and 4.

The narrowest slabs, or slabs of the second cutting, will be separated from the log in the operation of sawing, but the widest slabs will adhere to the core of the log, and may be readily detached therefrom, by sawing or splitting.

I am aware that it is not new to saw a log in a direction with the length of the grain of the wood, and in planes radiating from the axis of the log. This mode of sawing produces planks which are in cross-section triangular, and, if the logs are not very large in diameter, each plank, when properly dressed to an even thickness from one edge to the other, will necessarily be much narrower than half the diameter of the log from which it was sawed.

I also am aware that, with the ordinary saw-mill, it is a very common practice to saw logs into planks having parallel sides, that is, sawing in planes which are tangential to circles described concentric to the axis of the logs. Under this mode the saw passes from side to side of the logs, and, therefore, no two planks sawed from the same round log are of the same width. If the logs were squared, or "slabbed" previously, this would not be the case, it is true, but by slabbing, or squaring, great waste occurs, and, beside this, this mode of sawing does not produce, I believe, as good stave-stuff as my mode does.

By my improved machine, and method of sawing round logs with the grain, I am enabled to produce stuff which is ready for the well-known stave-shaping machinery, without dressing.

Having described my invention,

What I claim as new, and desire to secure by Letters Patent, is—

1. The mode herein described of sawing stuff with parallel sides, from round logs.

2. The arrangement of the two laterally and vertically-adjustable centres, with the circular saw, substantially as described.

3. The combination of the slotted portions E e, of head-blocks, centres G G', slides F F', and clamping-nuts e e, the said parts being constructed and arranged and operated substantially as described.

4. The combination of the centre G', screw s, and clamping-devices F' d e, with the slotted head-block D E, substantially as described.
